W. E. CRAWFORD

VALVE OR WELL CAPPER

Filed April 5, 1923

FIG. 1.

UNITED STATES PATENT OFFICE.

WILLIAM E. CRAWFORD, OF HAVRE, MONTANA.

VALVE OR WELL CAPPER.

Application filed April 5, 1923. Serial No. 630,146.

To all whom it may concern:

Be it known that I, WILLIAM E. CRAWFORD, a citizen of the United States, residing at Havre, in the county of Hill and State of Montana, have invented certain new and useful Improvements in Valve or Well Cappers; and I do hereby declare the following to be a full, clear, and exact description of the invention, such as will enable others skilled in the art to which it appertains to make and use the same.

This invention relates to a valve and it aims to provide a novel and efficient construction adapted for use to cap wells to prevent the gushing of oil, gas or water therefrom.

It is particularly aimed to provide a construction which may be operated while the cable or rope as ordinarily used to suspend the auger or drilling means is in place, to the end that the capping or operation of the valve may be more expeditious.

Another object is to provide a particular construction wherein the valve means co-acts with the said rope or cable in order to cap the well.

Still another object is to provide a novel construction whereby the valve may be actuated from a distance as in cases of fire.

It is also aimed to provide a novel construction embodying the various details, combinations and arrangement of the parts hereinafter described and illustrated in accompanying drawings.

In said drawings:

Figure 1 is a view in vertical section showing the valve in place in a well casing;

Figure 2 is a view on an enlarged scale looking interiorly of the valve and with one of the sections of the casing removed;

Figure 3 is an end elevation of the valve, and

Figures 4 and 5 are respectively cross-sectional views through the valve taken on the lines 4-4 and 5-5 of Figure 2.

Like reference characters designate like or similar parts in the different views.

In reducing the invention to practice, a suitable casing is provided as at 10 for instance made in metallic sections 11 and 12, either of which may be uppermost. The sections 11 and 12 are preferably separably connected together as by means of bolts at 13. Section 11 is substantially a plate while section 12 is of dished formation. Each sec-

tion 11 and 12 has alined openings 14 disposed transversely therethrough and surrounded by collars 15 in the form of flanges integral with and extending from the sections 11 and 12. Sections of a well casing as indicated at 16 are adapted for connection to the collars 15 for instance, by screw threads as shown at 14. In this way, the casing 10 is connected to the well casing but it is to be understood that any other preferred manner or means tending toward this end may be utilized. 17 designates the rope or cable used to suspend the auger (not shown) or other drilling means from a point above the well and which suspending member 17 passes through the sections 16 and the casing sections 11 and 12 as shown in Figure 1.

Casing section 12 is inwardly depressed in order to provide a ledge 18 along which a metallic valve plate 19 is adapted to slide. An actuating rod or stem 20 is screw threaded in one end of the casing section 12 and at its other end is adapted for connection to the valve so as to slide the latter through turning of said stem 20. In this connection, stem 20 adjacent its free end may have an annular groove 21 engaged by spaced fingers 22 extending at an angle and integrally from the plate 19. As a result of this construction, when the sections of the casing are separated, the valve plate 19 may be readily removed or disengaged from the stem 20. An operating wheel 23 may be provided on the stem 20 and adapted for manual operation if desired but preferably adapted for actuation through the medium of a belt or flexible element 24 trained in a peripheral groove of said wheel. This element 24 permits actuation of the device from a distance which is advisable in case of a fire in or adjacent the casing.

The distal end of the valve plate 19 is adapted to engage the cable or suspending element 17 and at the zone of engagement, said plate is preferably notched as at 26 to fit and accommodate said cable or suspending element 17.

In practice the valve plate 19 is usually maintained as far as practical to the right in Figure 1 or at least out of alinement with the openings 14. Should it be desired to close the well or casing represented by sections 16, for any reason, as in case of fire, or a heavy flow of gas or water attending a

gusher, the stem 20 is turned, preferably through manipulation of the flexible element 24 since it may be operated at a distance from the well although if desired the 5 wheel 23 may be manually gripped by the hand and thus operated. The valve is through operation of said stem 20 slid over the openings 14 to close them inasmuch as the valve is of a thickness equal to the depth 10 of the depression above the ledge 18 and engages both said ledge 18 and the under surface of section 11. Such sliding movement causes valve 19 to engage that portion of the suspending element 13 in its path, thus 15 compressing or intimately engaging and accomodating the cable at notch 26 and the adjacent end wall of section 12. When the cable is thus engaged, the edge of the plate 19 on each side of the notch 26 inti- 20 mately engages the adjacent end wall of the section 12. The well may thus be promptly and effectively closed by the valve plate in combination with the cable or suspending element 17. This is particularly advanta- 25 geous since it does not require removal of the suspending element or cable 17 in order to close the well or its casing.

Changes may be resorted to within the spirit and scope of the invention.

I claim as my invention:—

1. A valve device of the class described having a casing, in combination with a tool-suspending means passing therethrough, and a valve having a notch to receive said means, said valve being operable in the casing to 35 engage an end wall thereof and to move said means into engagement therewith.

2. A valve device of the class described having a casing in sections separably connected together, in combination with a tool-suspending means passing through the casing, one of the sections having a ledge, a valve plate slidable on said ledge and engageable at one end with the walls of the casing section, said end having a notch to 45 receive said suspending means and wedge it against said ledge and an operating means for said valve.

In testimony whereof I affix my signature in presence of two witnesses.

WILLIAM E. CRAWFORD.
